PORTABLE DRILLING MACHINE

Karl H. Andren, Milwaukee, Wis., assignor to
 Artos Engineering Company, Milwaukee, Wis.,
 a corporation of Wisconsin

Application April 9, 1932, Serial No. 604,169

16 Claims. (Cl. 77—7)

The present invention relates in general to improvements in the art of assembling composite structures formed of elements such as metal plates and bars, and relates more specifically to improved apparatus for producing rivet holes or other perforations in loosely assembled beams or girders comprising coacting parts such as steel plates and structural bars of varied cross-section.

In the assembly of structural steel beams, girders and similar members, formed of plates and cooperating bars, it has heretofore been customary to punch or drill the rivet holes in the individual elements prior to assembly, and to subsequently ream the adjacent holes into perfect alignment after loose assembly of the member had been effected and preparatory to final riveting. In large or relatively complex structural members of this type, it has always been difficult to insure correct disposition of the rivet holes so as to avoid excessive reaming and alining of the holes during final assembly of the structures. Such reaming is not only costly, but also prevents production of properly located holes having uniform and desired diameter. The assembly of such beam or girder structures with the prior art methods, has therefore been expensive, slow and inaccurate, and the final structures were imperfect.

It is an object of the present invention to provide an improved method of and apparatus for simplifying the mode of assembling structural steel or other composite members, by the provision of simple and highly efficient means for producing properly positioned rivet holes of uniform and accurate diameter, without necessity of reaming such as was previously required.

Another object of the invention is to provide improved mechanism for suspending and for positioning a perforating machine such as a drill press, so that the machine may be readily conveyed throughout quite an extended area of operation, and readily manipulated to produce holes at any desired angle in various portions of a relatively complex structure.

A further object of the invention is to provide a combined perforator and work clamp, which can be readily adjusted to different positions relative to the work, and which can be easily manipulated to clamp various portions of a laminated or other composite structure into intimate contact with each other.

Still another object of the invention is to provide improved means for eliminating necessity of either furnishing a specially constructed rigid and costly support for a perforating ma-

chine such as a drill or punch press, or providing such a support for the structure to be perforated and assembled.

Another object of the invention is to provide an improved perforating machine such as a punch or drill press, which is especially adapted to produce alined holes in a series of laminations or plates coacting with each other.

A further object of the invention is to provide a portable perforator unit such as a drill press, which is clamped into operative position upon the work, rather than having the work supported by or clamped to the perforating machine itself, whereby large pieces of work can be conveniently perforated with minimum effort by virtue of the lightness, compactness and convenient portability of the perforating unit.

Still another object of the invention is to provide improved clamping means for holding layers of material in firm coaction with each other and for preventing separation of the layers, so that chips or other foreign matter cannot get between the laminations during the perforating operation.

Another object of the invention is to provide an improved clamp for holding a portable perforating machine so as to positively position the work at the proper angle, usually perpendicular, relative to the direction of movement of the perforating tool.

A further object of the invention is to provide an improved clamping media which is adapted to effectively resist twisting or angular displacement of the work about the axis of travel of the perforating tool, such as is induced by the torque in a rotary perforator or drill operated by a portable prime mover.

Still another object of the invention is to provide means for quickly and effectively manipulating work clamping mechanism, and for effecting abnormal opening of the clamping jaws so as to permit convenient application, shifting and removal of the mechanism.

Another object of the invention is to provide improved mechanism for effecting either automatic or manual clamping and release of the work, and similar interchangeable operation or withdrawal of the perforating tool of a machine.

A further object of the invention is to provide an improved toe clamp structure or clamp rail mounting for effecting utilization and movement of a perforating machine in conjunction with a flat object or piece of work.

Still another object of the invention is to provide improved instrumentalities for effecting va-

riation in the direction or extent of the perforations, and of the effective clamping, without changing the structure of the perforating unit and also without shifting the work.

5 Another object of the invention is to provide improved means for counter-balancing the weight of a portable perforator so as to facilitate movement and manipulation thereof.

10 A further object of the invention is to provide an improved movable or swinging suspension cooperating with the center of gravity of a drilling or punching unit, whereby the perforating tool may be conveniently brought into alignment with center punch holes or other marking media.

15 Still another object of the invention is to provide an improved hinge system for movably suspending a machine, and means for counter-balancing the weight of the machine, wherein the counter-balancing means does not interfere with 20 the free use of the hinged suspension system.

These and other objects and advantages will be clearly apparent from the following detailed description.

25 A clear conception of embodiments of the various features of the present improvement and of the construction and mode of operation of portable drills and clamping devices built in accordance with the invention, may be had by referring to the drawings accompanying and forming a part 30 of this specification in which like reference characters designate the same or similar parts in the various views:

Fig. 1 is a somewhat diagrammatic side elevation of an improved drill press and of a suspension device therefor, showing the press associated with a laminated member preparatory to drilling horizontal holes through depending flange portions of the member;

Fig. 2 is a similar view of the drill press showing 40 the same associated with another portion of the laminated member preparatory to the drilling of vertical holes through the member just within the flanged edge thereof, the press being provided with a modified form of clamp;

Fig. 3 is a similar view of the drill press showing 45 the same associated with an upwardly projecting flange portion of the laminated member preparatory to drilling horizontal holes through said portion with the aid of a clamp similar to that utilized in the assemblage of Fig. 1;

Fig. 4 is a relatively diagrammatic side elevation of the improved drill press, showing the same in use for drilling vertical holes in the medial portion of a laminated member, with the aid of a special clamp;

Fig. 5 is a front view of the assemblage illustrated in Fig. 4, showing the special clamp more in detail;

Fig. 6 is an enlarged front view of the improved 60 portable drill press and of a fragment of an improved clamp of the form shown in Fig. 2;

Fig. 7 is a similarly enlarged part sectional front view of the drill press, the section being taken along the irregular line 7—7 of Fig. 10;

Fig. 8 is a likewise enlarged central vertical section through the drill press, taken along the line 65 8—8 of Fig. 9;

Fig. 9 is a top part sectional view of the improved portable drill press, drawn to the same scale as Fig. 6, and with the upper gear case cover removed, the section being taken along the line 9—9 of Fig. 8;

Fig. 10 is a transverse horizontal section through the drill press, taken along the irregular line 10—10 of Fig. 8 and drawn to the same scale;

Fig. 11 is a side view of the improved drill press drawn to the scale of Fig. 6 and looking toward the right of the device as viewed in the latter figure;

Fig. 12 is a fragmentary vertical section 5 through the drill press, taken along the line 12—12 of Fig. 9;

Fig. 13 is a fragmentary vertical section through the drill press, taken along the line 13—13 of Fig. 9;

Fig. 14 is a fragmentary horizontal section 10 through the drill press, taken on the line 14—14 of Fig. 7;

Fig. 15 is a fragmentary vertical section 15 through the drill press, taken on the line 15—15 of Fig. 14;

Fig. 16 is a further enlarged fragmentary part 20 sectional top view of the control valve and actuating mechanism for the improved portable drill press;

Fig. 17 is a similarly enlarged vertical section 25 through a portion of the control valve and actuating mechanism, the section being taken along the line 17—17 of Fig. 16;

Fig. 18 is another similarly enlarged vertical 30 section through the control valve and actuating mechanism, taken on the irregular line 18—18 of Fig. 16;

Fig. 19 is still another likewise enlarged vertical 35 section through a fragment of the control valve and actuating mechanism, taken along the line 19—19 of Fig. 16;

Fig. 20 is a similarly enlarged horizontal section 40 of a fragment of the control valve mechanism, taken on the line 20—20 of Fig. 17;

Fig. 21 is a diagram showing the drill press 45 control valves in one operative position for vertical drilling, with the spindle balanced prior to application of the power and with clamp released;

Fig. 22 is another diagram of the control valves, 50 showing the same in position corresponding to clamping preparatory to drilling and with the drill spindle being driven;

Fig. 23 is still another diagrammatic disclosure 55 of the control valves positioned to maintain the clamp closed and with the drill spindle ready for withdrawal directly after completion of a hole;

Fig. 24 is a further diagrammatic showing of 60 the control valves at the time the drill leaves the hole and just prior to release of the clamp;

Fig. 25 is a similar showing of the control valves during release of the clamp and with the drill spindle disengaged from the advancing mechanism;

Fig. 26 is a diagram of the valve for controlling 65 the balancing cylinder, showing the port arrangement for horizontal drilling;

Fig. 27 is a diagram of the balancing cylinder;

Fig. 28 is a diagram of the clutch control cylinder; and

Fig. 29 is a diagram of the clamp actuating cylinder.

Referring specifically to Figs. 1 to 5 inclusive, it will be apparent that the present invention comprises in general an improved portable power driven drilling unit 30 which is angularly adjustably mounted upon a carrier member or yoke 31 forming a part of the unit; a clamping device detachably associated with the drill unit 30 near the tool supporting spindle of the latter; vertically movable flexible suspension means 32 co-acting directly with the carrier yoke 31; laterally adjustable supporting means 33 for the suspension means 32; and means for supplying fluid

under pressure such as air, to a plurality of actuating valves and cylinders forming part of the drill press or unit 30. The drill press or unit 30 will be described in detail in conjunction with Figs. 6 to 29, and the means for supplying compressed air or the like to the unit 30, may consist of flexible tubes of usual form communicating with a storage supply tank (not shown). Depending upon the specific use to which the apparatus is to be put, the clamping device or mechanism will assume either of three different forms.

As shown in Figs. 1 and 3, for horizontal drilling of flanged edges portions of a laminated member or beam 34, the clamp comprises a rigid reach arm 35 movably supported upon the drill unit 30 for sliding movement parallel to the axis of the drill spindle and carrying one or more reaction elements 36 which are adjustable longitudinally of the spindle axis, and a series of three legs 37, 38 adjustably associated with a clamp bracket 39 which is detachably secured to drill unit frame concentric with the drill carrying spindle. The mechanism for supporting and for effecting sliding movement of the clamp arm 35 will be subsequently more fully described, and the reaction elements 36 should preferably be so formed and disposed that they will not interfere with the passage of a drill 40 through the laminations of a beam 34 being perforated. The legs 37 which are located in front and in back of the drill 40, have plain ends for engaging the beam 34, but the third leg 38 of the tripod, has an end roller 41 cooperable directly with the beam 34. The legs 37, 38 obviously coact with the side of the beam 34 on which the drill unit 30 is disposed, while the elements 36 react against the opposite side of the beam and within the zone of action of the legs 37, 38 and drill 40, so that when the clamp arm 35 is moved toward the drill unit 30, the elements 36 cooperate with the legs 37, 38 to firmly clamp the intervening laminations of the beam 34 together. The adjustability of the elements 36 and legs 37, 38 will permit use of the clamp with beams 34 of various thicknesses and comprising a varied number of laminations.

As illustrated in Fig. 2, for vertical drilling of portions of the member or beam 34 within a limited distance from the opposite flanged edges thereof, the clamp comprises an upper arm 42 and a lower arm 43 connected to the upper arm 42 by means of a link 44, and a tripod having legs 37, 38 identical with those previously described both in structure and mode of mounting. The upper arm 42 is again movably supported upon the drill unit 30 for sliding movement parallel to the axis of movement of the drill 40, and the lower arm 43 also carries one or more reaction elements 36 which are adjustable longitudinally of the drill axis. The clamp arms 42, 43 are relatively flexible and extend beyond the pivots which connect these arms to the ends of the link 44. A strut 45 is pivotally attached to the projecting end of the upper arm 42 and normally coacts with the projecting end of the lower arm 43 as shown in full lines in Fig. 2, but when the clamping pressure has been released, the strut 45 may be swung out of contact with the lower arm 43 to thereby permit the lower arm to drop to the position shown in dot and dash lines. The clamp may then be moved freely over the flanged edge of the beam 34, or the drilling unit 30 may then be elevated entirely away from the beam without interference by the clamp arm 43. As in the case of the horizontal clamp disclosed in Figs. 1 and 3,

the vertical edge clamp of Fig. 2 has the tripod legs 37, 38 disposed on the drill side of the beam 34 while the reaction elements 36 are located on the opposite side thereof within the zone of action of the legs 37, 38 and drill 40, so that movement of the lower arm 43 toward the drill unit 30 will effect firm clamping of the intervening laminations. This modified clamp may likewise be adjusted to accommodate beams 34 of various thicknesses, and additionally provides for free removal from the work by virtue of the removable strut 45.

While the clamps shown in Figs. 1, 2 and 3 are well adapted for use when perforating edge portions of a member or beam 34, they cannot be effectively utilized when forming holes in medial portions of wide beams 34, remote from the beam edges. For such use, a clamp of the form illustrated in Figs. 4 and 5 may be employed. This special clamp is especially adapted for vertical drilling and comprises a stiff reaction bar 46 which is adapted to be mounted parallel to the drill side of a beam 34 by means of spacing collars 47 and bolts 48. The bar is secured to the upper overhanging ends of curved press-arms 49 the opposite lower ends of which coact directly with the member or beam 34 and the medial portions of which are clamped to the upper ends of the collars 47 by the bolts 48 as clearly indicated in Fig. 5. The holes in the beam 34, with which the clamping bolts 48 coact, may be formed with the aid of a clamp and drill press assembly such as shown in Fig. 2, and the unit 30 is movable along the reaction bar 46 to produce a series of parallel holes across the medial portion of the beam 34. The unit 30 of Figs. 4 and 5, is provided with a tripod consisting of a bracket 39 attached to the frame of the unit, and legs 37, 38 adjustably associated with the bracket 39 and engaging the beam 34 at three points around the drill. This unit 30 is also provided with a hook arm 50 which is movable vertically to produce a clamping effect against the beam 34 at the zone of drilling. The hook arm 50 is vertically slidable relative to the frame of the unit 30 and has an adjustable element 51 cooperable directly with the lower face of the bar 46, and upon release of the clamping pressure, the unit 30 may be slid along the bar 46 while resting upon the roller 41.

From the foregoing specific descriptions of the three different types of clamps, it will be apparent that by interchangeably associating these clamps of Figs. 1 to 5, inclusive, with a common drilling unit 30, effective clamping and drilling of any portion of a laminated member or beam 34 may be readily effected.

The vertically movable flexible suspension means 32 which coacts directly with the carrier yoke 31 of the unit 30, is illustrated in detail in Fig. 1, and comprises a chain 52 coacting with a sprocket 53. One end of the sprocket chain is attached to the yoke 31 by means of a swivel 54, and the opposite chain end is secured to a cable 55 which passes over and under a series of sheaves 55' and has a counter-balance weight 56 secured to the end thereof remote from the chain 52. The weight 56 serves to substantially balance the weight of the unit 30 and yoke 31, and the sprocket 53 is rotatable to either raise or lower the chain 52, by means of a hand hoist 57 which due to the counterbalancing afforded by the weight 56, requires but little effort for operation. With the aid of the suspension means 32 just described, the drilling unit 30 may be conveniently and quickly elevated or lowered as 75

desired, and subsequently suspended in a definite horizontal plane.

The laterally movable supporting means 33 upon which the suspension means 32 is mounted, is likewise shown in detail in Fig. 1, and comprises a series of pivotally connected brackets 58, 59, 60 the former of which is swingable relative to a fixed or a traveling support 61, about a vertical hollow pivot 62. The opposite ends 10 of the intermediate bracket 59, are swingable relative to the adjacent ends of the end brackets 58, 60 about similar hollow pivots 63, 64 respectively. The sheaves 55' are rotatably supported by the brackets 58, 59, 60 so as to guide the 15 vertical portions of the cable 55 in line with the pivotal axes of the brackets, and thus permit the counter-balancing weight 56 to function without interference by the movement of the brackets 58, 59, 60 relative to each other. It 20 will be obvious, that by moving the brackets 58, 59, 60 of the supporting means 33 relative to each other and to the support 61 about the vertical pivots 62, 63, 64, the free end of the bracket 60 which carries the unit 30, may be moved to any desired position throughout quite 25 an extended horizontal area, without in any manner interfering with vertical or angular adjustment of the unit 30.

From the foregoing specific description of the 30 suspension mechanisms, it will be apparent that the unit 30 may be universally moved or adjusted, either about its own horizontal axis of suspension, or vertically, or horizontally, throughout a considerable range, thereby permitting cooperation of the unit with any portion 35 of a fixedly supported beam 34 of great length and breadth having edge flanges of considerable height and of various angles. This portability of the perforating unit 30, avoids necessity of moving the relatively heavy piece of 40 work or beam 34, and the movement of the drill press is greatly facilitated by the counter-weight 56 which substantially counter-balances the weight of the portable unit 30.

The construction and mode of operation of the 45 improved drilling unit 30 will be clearly apparent by reference to Figs. 6 to 29 inclusive. This unit 30 comprises in general a main frame 65 which is angularly adjustable relative to its carrier yoke 61, and provides a support for a rotary 50 axially movable drill spindle 66 and for the spindle driving motor 67, see Figs. 6, 7, 8 and 11. The frame 65 has a through bore along which 55 a carriage 68 is slidable, and the spindle 66 which carries a chuck 69 cooperable with drills 40 of various sizes, is rotatably supported in and is fixed against longitudinal movement relative to the carrier by ball bearings 70 mounted in the upper and lower ends of the carrier 68, see Fig. 8. The carriage 68 is longitudinally 60 movable to feed and to withdraw the drill 40 and spindle 66, by means of a pinion 71 coacting with a rack 72 at one side of the carriage, and the carriage 68 is prevented from rotating within 65 its guiding bore by means of a spline 73 cooperating with a groove 74 formed in the frame 65. The end of the spindle 66 remote from the chuck 69, is longitudinally grooved for sliding coaction 70 with a spur gear 75 which is secured to a rotary bushing 76 mounted in ball bearings 77 supported by a sleeve 78 secured to the upper end of the frame 65, see Figs. 8 and 9. While the gear 75 is freely rotatable about the axis of the spindle 66 so as to impart rotation to the spindle 75 and to the drill 40 associated therewith, this gear

is fixed against axial displacement, and meshes with a pinion 79 carried by a counter shaft 80. The counter shaft 80 is rotatably mounted in ball bearings 81 removably supported by the frame 65, and also carries a second pinion 82 which meshes with a spur gear 83 secured to an end of a second counter shaft 84. The second counter shaft 84 is rotatably supported in ball bearings 85 carried by the frame 65, and has another spur gear 86 secured to its opposite end and meshing with a driving pinion 87. The pinion 87 is driven directly by the driving motor 67 through the motor shaft 88. The motor 67 may be of the electric type, and the speed reducing gears 83, 82 are preferably removable from their supporting shafts so as to permit substitution of other gears therefor, for the purpose of changing the speed of rotation of the spindle 66. In order to facilitate such interchange of gears, the frame 65 is provided with a removable end cover 89, and a tubular extension 90 within which the grooved driving end of the spindle 66 is longitudinally movable is also provided, see Fig. 8.

While the main function of the electric motor 67 is to rotate the spindle 66 and to advance the same for feeding of the drill, other means operable by fluid such as air under pressure are provided for withdrawing the same upon completion of the drilling operation. This drill spindle balancing and withdrawing means comprises the 30 carrier 68 and rack 72, and an air actuated servomotor consisting of a cylinder 91 and piston 92 best illustrated in Figs. 7, 8, 10 and 27. The piston 92 is rigidly attached to a rod 93 which is movable parallel to the drill spindle 66, and the end of which is provided with a rack 94 coacting with the pinion 71 which also coacts with the rack 72 of the spindle carrier 68. The rack 94 is movable longitudinally within a hollow clamp guide 95 attached to the main frame 65, and the pinion 71 is supported by a shaft 96 journaled in the frame 65 and provided with a hand wheel 97. The pinion 71 and its supporting shaft 96, are provided with a central bore within which a rod 98 is slidably disposed, and this rod 98 is movable longitudinally by means of a push button 99 located centrally of the hand wheel 97. The shaft 96 also carries a spur gear 100 as shown in Figs. 10 and 12, which meshes with a pinion 101 secured to one end of the clutch shaft 102 journaled in the frame 65, and the opposite end of the shaft 102 has a jaw clutch member 103 formed integral therewith. While the shaft 102 and member 103 are rotatable about the shaft axis, these elements are not movable along the 55 shaft axis.

Disposed coaxial with and adjacent to the end of the shaft 102 remote from the pinion 101, is a short shaft 104 which is rotatably supported in bearings 105, 106 the latter of which is carried within the clutch member 103. The portion of the shaft 104 between the bearings 105, 106 is connected by splines to another clutch member 107 which is interlockable with the member 103 to produce a positive driving connection between the coaxial shafts 102, 104. The clutch member 107 is constantly rotatable with its supporting shaft 104 and is slidably therealong by means of a fork 108 which is movable by arms 109 carried by a pivot shaft 110 supported on the frame 65 as shown in Figs. 12, 14 and 15. The pivot shaft 110 is rockable by means of a lever 111 the swinging end of which is connected with the plunger rod 112 of a fluid pressure actuated servo-motor, by a link 113. The cylinder 114 75

of this clutch actuating servo-motor is mounted in brackets 115 secured to the frame 65, and the servo-motor plunger 116 is secured to the rod 112 within the cylinder as shown in Fig. 28. This servo-motor is obviously capable of actuating the jaw clutch consisting of the members 103, 107 to either drivingly connect, or to disconnect the aligned shafts 104, 102. The clutch actuating servo-motor may be of relatively small dimensions since but a slight amount of power is required to move the jaw clutch member 107 into and out of engagement with the member 108, and the mounting of this servo-motor is such that it is conveniently accessible from the exterior of the drill or perforating unit 30.

Secured to the overhanging end of the shaft 104, remote from the bearing 106, is a worm wheel 117 which meshes with a worm 118 secured to a shaft 119, and this shaft 119 is also journaled in a housing carried by the frame 65 and carries a pinion 120 which meshes with another pinion 121 secured to one end of a counter-shaft 122 journaled in the frame 65, see Figs. 12 and 13. The opposite end of the shaft 122 carries a worm wheel 123 which meshes with a worm 124 secured to the end of the counter-shaft 80 remote from the pinions 79, 82 as shown in Figs. 8 and 13, so that when the electric motor 67 is operating, the rotation of the shaft 80 is imparted through the worm gearing 124, 123, shaft 122, pinions 121, 120, shaft 119, worm gearing 118, 117, and shaft 104 to the movable clutch member 107. When this clutch member 107 is interlocked with the clutch member 103, by the clutch actuating servo-motor of Fig. 28, the pinion 71 is being power operated to impart drill feeding motion to the carrier 68 and spindle 66, through the shaft 102 and gears 101, 109, but when the clutch members 103, 107 are disengaged, the carrier 68 and spindle 66 are free to be moved in either direction by the hand wheel 97 secured to the shaft 96. It will also be apparent that with the clutch members 103, 107 thus disengaged, the pinion 71 is free to be operated by the piston 92 and rod 93 of drill withdrawing servo-motor of Fig. 27, and both the manual and automatic functioning of these servo-motors will be subsequently described more in detail.

The clamp actuating mechanism which is carried by the drill unit 30 and which functions to automatically clamp the work or beam 34 prior to drilling, is best illustrated in Figs. 6, 7, 10 and 11. While the same clamp actuating mechanism serves to interchangeably operate either of the three types of clamps shown in Figs. 1, 2 and 5, the mechanism will be described only in connection with the type of clamp shown in Fig. 2, it being understood that the construction and operation of the actuating mechanism remains the same for all types of clamps. This clamp actuating mechanism comprises a yoke 125 to which the upper clamp arm 42 is rigidly attached and which is guided to move parallel to the drill spindle axis; a pair of slides 126 secured to the yoke 125 by cap screws 127 and movable in guideways 128 disposed on opposite sides of the main frame 65; a clamp actuating servo-motor 129 pivotally suspended from the frame 65; and linkage connecting the piston rod 130 of the servo-motor with both of the slides 126. The clamp actuating servo-motor is shown in section in Fig. 29, and consists of a cylinder 131 having a piston 132 secured to the rod 130, upper and lower ports 133, 134 respectively for admitting and exhausting fluid such as air under pressure to and from the

cylinder 131, and control valve mechanism for regulating the admission and exhausting of the air. The cylinder 131 is swingably supported upon the pivot 135 and the outer end of the piston rod 130 is pivotally connected to the upper arm of a lever 136 which is secured to a cross-shaft 137 journaled in a bracket secured to the main frame 65. The lower arm of the lever 136 is pivotally attached to the upper end of a link 138, and the end of the shaft 137 on the opposite side of the machine carries a similar arm likewise attached to another link 138. The lower ends of the links 138 are pivotally connected to the central arms of T-levers 139, corresponding ends of the cross-arms of which are pivotally attached to fixed brackets 140, and the opposite corresponding ends of the cross-arms of which are pivotally attached to the lower ends of links 141, as viewed in Fig. 7. The upper ends of the links 141 are pivotally connected to the slides 126, and these slides are recessed as shown for the reception of the T-levers 139, brackets 140 and links 141. With this assemblage of elements, it will be apparent that when the piston 132 of the servo-motor 129 is moved, the rod 130 will oscillate the cross shaft 137 through the lever 136, and the movement of the shaft 137 will be transmitted through the two sets of links 138, T-levers 139 and links 141 to the slides 126 to cause these slides to move in the parallel guideways 128. This parallel movement of the slides 126 will be imparted to the yoke 125 and from thence to the clamp arm 42, to produce either a clamping or a clamp releasing effect, dependent upon the direction of movement of the servo-motor piston 132. The pivot 135 upon which the cylinder 131 is suspended, will permit the servo-motor to swing freely as indicated in dot and dash lines in Fig. 7, when the lever 136 and shaft 137 are oscillated.

As previously indicated, the perforating unit is angularly adjustably suspended from the yoke 31, the unit being swingable about a horizontal axis located near the center of gravity thereof. The mechanism for thus angularly displacing the unit 30 relative to the suspension yoke 31 and for locking the same in adjusted position so as to permit drilling in various angular directions, is best illustrated in Figs. 6, 9, 10, 11 and 12. This adjusting mechanism comprises a worm 142 rotatably supported in bearings 143 attached to the frame 65, and having a polygonal head 144 formed integral therewith and adapted for co-operation with a socket wrench in order to turn the worm 142. The worm 142 meshes with a worm wheel 145 secured to a cross-shaft 146 which extends transversely through the unit 30 and is journaled in a bracket on the frame 65 thereof. Secured to each end of the cross-shaft 146 is a spur pinion 147 and each of these pinions meshes with a spur gear 148. The spur gears 148 are rotatably supported upon stub shafts 149 fixedly attached to the main frame 65, and are adapted to coact with the ends of the suspension yoke 31 through lugs 150 formed integral with the gear peripheries. The common axis of the stub shafts 149 penetrates the perforating unit 30 near the center of gravity thereof, and the loose coaction between the lugs 150 and yoke 31, permits the unit 30 to swing freely to a small extent, at all times. It will be apparent, that by rotating the worm 142 with the aid of a wrench applied to the head 144, rotation will be imparted through the worm wheel 145 and shaft 146 to the pinions 147, and these ro-

tating pinions 147 will roll along the peripheries of the fixed gears 148 until the rotation of the actuating worm 142 stops. The drill unit 30 may thus be adjusted to any desired angular position 5 relative to the suspension yoke 31 and about the axis of the stub shafts 149, and the worm 142 co-acting with the worm wheel 145 serves to effectively lock the unit 30 in adjusted position. If so desired, a suitable gage for approximately determining the degree of angular adjustment, may be provided.

From the preceding description, it will be noted that the improved perforating unit 30 is provided with three fluid pressure actuated servo-motors, namely the drill spindle balancing and withdrawing servo-motor shown in Fig. 27, the clamp actuating servo-motor of Fig. 29, and the clutch actuating servo-motor illustrated in Fig. 28. For convenience, these servo-motors 10 will be designated as the balancing, clamp and clutch servo-motors respectively. The admission and exhaust of compressed air to and from these servo-motors is controlled by an improved assemblage of valves which are shown in enlarged 15 form in Figs. 16 to 26 inclusive, and the interconnection between these several control valves and the servo-motors is also illustrated in Figs. 6, 7, 8, 9, 11, 14 and 15. This assembly comprises three main piston valves 151, 152, 153 and 20 a pilot or actuating valve 154 slidable within the main valve 152. The main valve 151 controls the balancing servo-motor, and the main valve 153 controls the clutch servo-motor, while the main valve 152 and auxiliary valve 154 control the 25 clamp servo-motor. All of the main valves 151, 152, 153 are slidably mounted in a common valve casing 155 which is detachably secured to the upper portion of the main frame 65 of the unit 30, and a valve actuating rod 156 which is 30 slidable longitudinally and parallel to the drill spindle axis, is also slidably and rotatably supported in the casing 155 and frame 65. The single actuating rod 156 at times cooperates with all of the main valves 151, 152, 153, and while it would 35 appear from the diagrams illustrated in Figs. 21 to 25 inclusive, that there are two rods 156, there is in fact only one such rod and the apparent duplication of this element in these diagrams, has been made merely for the sake of clearness.

40 The lower portion of the actuating rod 156 which coacts with the main frame 65 directly adjacent to the pinion 71 and clutch servo-motor as shown in Fig. 8, is provided with a pair of vertically spaced collars 157, 158 having lateral 45 projections which are, under certain conditions of operation, engageable with a fixed pin 159 carried by the piston rod 93 of the balancing servo-motor as clearly shown in Figs. 7 and 11. The collars 157, 158 may be adjusted to different positions along the rod 156 so as to change the time 50 of contact with the pin 159, and it will be apparent that when the drill spindle 66 is feeding the drill 40 forward, the pin 159 approaches and eventually engages the collar 157 to move the rod 156 upwardly, whereas reverse or withdrawal 55 motion of the spindle 66 and drill 40 will eventually cause the pin 159 to engage the collar 158 and move the rod 156 downwardly. In addition to this action produced by the motion of the spindle 66 and drill 40 due to feeding of the drill 60 by the motor 67, and withdrawal thereof by the hand wheel 91, movement of the piston rod 93 by fluid pressure applied to the piston 92 will also cause engagement of the pin 159 with the collars 157, 158, and the rod 156 is furthermore manually 65

shiftable and rotatable with the aid of a handle 160 secured thereto between the collar 157 and the valve casing 155 as shown in Fig. 16. The extreme upper end of the actuating rod 156 is provided with an element 161 having spaced 5 flanges 162, 163 and also having a series of three notches 164 therein which are engageable by a spring pressed latch 165 as illustrated in Fig. 18. The flanges 162, 163 are approximately semi-circular in form as shown in Fig. 16, and the element 161 is locked to the rod 156 by a nut 166.

One end of the balancing servo-motor control valve 151 is provided with an abutment collar 167 which, with the rod 156 in normal position, projects into the recess formed by the element 15 flanges 162, 163 as shown in Figs. 16, 18, 21, 22, 23, 24 and 25, but the rod 156 may be rotated with the aid of the handle 160, as indicated in Fig. 16, to move the projections of the collars 157, 158 out of the path of travel of the rod pin 20 159. The collar 167 is of less thickness than the distance between the flanges 162, 163 so as to permit relative movement of the valve 151 and rod 156, and the opposite end of the valve 151 is provided with an adjusting handle 168 for 25 manually swinging this valve about its longitudinal axis through an angle of ninety degrees as indicated in Fig. 16, for horizontal disposition of the unit 30. The medial portion of the valve 151 adjacent to the handle 168 is provided with 30 parallel annular grooves 169, 170 connected by a transverse groove 171, and a spring pressed latch 172 mounted in the casing 155 is adapted to coact with the grooves 169, 170 and with detents located at the intersections of the grooves 35 169, 170 with the groove 171. The casing 155 is provided with a T-shaped fluid pressure supply conduit 173 which communicates with a supply pipe 174, and which also connects with an inlet or supply port for the valve 151. The valve 151 is provided with a longitudinal fluid passage 175 and with a lateral passage 176 communicating with the passage 175, and is furthermore provided with a longitudinal passage 177 disposed below the passage 176. These passages 175, 176, 40 177 are utilized when the valve 151 and its actuating lever 168 are positioned as shown in Figs. 16 and 18, and the unit 30 is to be operated with the drill 40 movable vertically. The valve casing 155 is also provided with upper and lower conduits 178, 179 disposed adjacent to the valve passage 175, with a conduit 180 communicable with the passage 176, and with an exhaust conduit 181. The conduits 178, 180 communicate directly with the upper end of the cylinder 81 of the balancing servo-motor, and the conduit 178 is provided with an adjustable control valve 182 for controlling the speed of travel of the piston 92.

45 The clamp control valve mechanism comprising the main valve 152 which is slidably supported by the casing 155 and the auxiliary valve 154 slidably mounted within the main valve 152, is shown in Figs. 16, 17, 21, 22, 23, 24 and 25. The upper end of the main valve 152 is provided with a collar 183 having a lateral projection 184 thereon which is of less width than the collar 167 on the valve 151 and which is likewise disposed in the recess formed between the rod flanges 162, 163. A handle 185 is formed integral with the collar 183, 50 and a fixed stop 186 secured to the casing 155, serves to limit the movement of the valve 152 and collar 183 away from the casing 155. The outer end of the auxiliary valve 154 is pivotally attached to one end of a link 187 the opposite end of which 55

is pivotally connected to the swinging end of a lever arm 188, see Figs. 11, 13, 14 and 15. The lever arm 188 is secured to one end of a pivot shaft 189 and the swinging end of a second lever arm 190 secured to the opposite end of the pivot shaft 189 is pivotally connected to the end of the push button rod 93, see Figs. 12, 13, 14 and 15. It will thus be noted, that when the push button 99 is pressed, the rod 93 will impart motion to the auxiliary valve 154 through the arm 190, pivot shaft 188, arm 183, and link 187, so as to move the valve 154 within the main clamp control valve 152. The valve 152 besides being slideable relative to the casing 155, is also rotatable by means of the actuating handle, as indicated in Fig. 16, so as to throw the projection 184 out of the path of travel of the rod flanges 162, 163. The auxiliary valve 154 is a pilot valve for controlling the admission of compressed fluid to and from the confined space at the lower end of the valve 152, and has superimposed annular passages 191, 192 which are alternately communicable with a longitudinal passage 193 formed in the valve 152. The valve 154 also has a central exhaust port 194 which connects with the lower annular passage 192 and with the atmosphere through the open end of the bore in which the valve 152 is slideable. The passage 193 of the valve 152 connects the confined space at the lower end of this valve with upper and lower transverse ports 195, 196, the former of which extends entirely through the valve 152 and connects with the intermediate of three superimposed longitudinal passages 197, 198, 199 formed on the side of the valve 152 opposite to the passage 193. The conduits 133, 134 which communicate respectively with the upper and lower displacement chambers of the clamp servo-motor cylinder 131, are disposed respectively above and below the supply conduit 173 for the valve 152, and two exhaust conduits 200 in the casing 155, are communicable through the passages 197, 199 with the conduits 133, 134 under certain conditions of operation. The delivery of compressed fluid from the conduit 173 to the valve 152 is also regulable by means of an adjustable needle valve 201 mounted in the valve casing 155, and the exhaust conduits 200 may likewise be provided with flow regulating valves located near the casing 155 as shown in Fig. 17.

The main clutch control valve 153 has an upper collar 202 provided with a lateral projection 203 which is constantly disposed in the recess between the flanges 162, 163 of the rod 93, and has an actuating handle 204 secured to the lower end thereof. This valve 153 is also provided with a series of three superimposed notches 205 which are alternately engageable with one end of a double spring pressed latch 206 the opposite end of which is engageable with notches 207 formed in a plate 208 secured to the valve casing 155. The casing of the latch 206 is fixedly attached to the swinging end of a lever 209 which is secured to one end of a pivot shaft 210 the opposite end of which carries a second lever 211. The swinging end of the lever 211 is pivotally connected to one of the parallel clamp moving slides 126 by means of a link 212, so that movement of the clamp yoke 125 and slides 126 will be imparted to the latch 206 through the link 212, lever 211, shaft 210 and lever 209. The clutch control valve is thus movable both by the handle 204 and rod 156, and by means of the latch 206, and the valve body has a series of three superimposed longitudinal passages 213, 214, 215 formed therein. The fluid supply conduit 173 is constantly communicable with the intermediate passage 214, and conduits 216, 217 communicate with the opposite ends of the clutch servo-motor cylinder 114, and exhaust ports 218, 219 are communicable respectively with the conduits 216, 217 through the upper and lower passages 213, 215.

All of the foregoing description of the control valves, applies primarily when the drill is being operated vertically, and the valve 151 must be rotated with the aid of the handles 168 as indicated in Fig. 16, when horizontal drilling is to be effected. The valve 151 is provided with a second set of passages 220, 221, 222 as shown in Fig. 26, which function during horizontal drilling, and these passages are communicable with the various conduits 173, 178, 179, 180, 181 in the valve casing 155, to actuate the drill withdrawing rod 93 horizontally. The valve 152 is likewise provided with special porting as shown in Fig. 20, for supplying unrestricted quantities of air to the lower face of this valve so as to produce quicker actuation thereof by the fluid pressure, but the precise mode of operation of the valves 151, 152 under these special circumstances, is relatively unimportant insofar as this invention is concerned. When operating the drill horizontally, it is unnecessary to counter-balance the weight of the drill spindle 66, as is done during vertical operation, and, the shifting of the valve 151 is primarily necessary in order to take care of this difference. It will be apparent that when the piston 92 which is attached to the rod 93 is subjected to pressure on both sides, the rod 93 is free to be moved in either direction by the hand wheel 97, and the difference in pressure on the opposite piston faces, due to the area of the rod, serves to counter-balance the weight of the carriage 63 and spindle 66, and it is this counter-balancing which becomes unnecessary during horizontal drilling. The porting of the valve 151 for horizontal drilling is therefore such that the opposite faces of the piston 92 are exposed to exhaust instead of to pressure, when hand wheel operation is desired.

As previously indicated, the improved portable perforating machine is susceptible of operation either by hand or automatically, at the will of the operator. The drill 49 is rotatable by the electric motor 67, and the three servo-motors 50 are adapted to automatically assist in the remaining operations and to facilitate hand control of said operations. One of these servo-motors actuates the clamping means; another of these servo-motors engages and releases the feeding clutch; and the remaining servo-motor functions to balance the weight of the carrier 63 and drill spindle 66, and provides additional power for withdrawing the spindle after a hole has been completed. Under ordinary conditions, these several operations will be automatically performed in proper sequence but provision is made for varying the timing of these several operations. These provisions take care of differences in operation during vertical and horizontal drilling, and also permit either automatic or hand control of the clamp at the end of each operating cycle. It will also be apparent that each of the several operations may at any time be controlled by hand, thus making the mechanism highly flexible in operation.

When ordinary automatic drilling is to be effected, the operation of the machine is substantially as follows. The unit 39 rests upon the legs 37, 38 which in turn coat with the beam 34.

which is to be drilled, and the weight of the unit 30 is substantially balanced by the counter-weight 56 coating with the flexible suspension means 32. The drill 40 is disposed vertically, and either 5 of the vertical clamping mechanisms shown in Figs. 2 or 5, may be utilized, although the description will be directed to the form of clamping mechanism shown in Fig. 2. The clamp arms 42, 43 are released, and the drill 40 is being rotated by the motor 67 through the gears 75, 79, 82, 83, 86, 87, but with the feed clutch disengaged. At the time, the weight of the drill carrier 68 and spindle 66 is counter-balanced by the admission of fluid under pressure to the opposite 10 sides of the piston 92, so that the drill 40 can be moved up or down with the aid of the hand wheel 97 without undesirable resistance.

With the elements of the unit thus positioned, the operator manipulates the hoist 57 to counter- 20 act the unbalanced weight and to lift the unit 30 slightly away from the beam 34. The unit is then floating and can be readily moved from one location to another, being suspended from the supporting means 33 which is preferably provided 25 with anti-friction bearings so as to permit convenient shifting of the unit. The operator may then manipulate the hand wheel 97 so as to move the rotating drill downwardly into a center punch mark or against any other mark point on the 30 beam 34. The finding of the exact location of such marking point is additionally facilitated by having the machine pivotally supported upon a swivel 54 and in the yoke 31, the latter support being near the center of gravity of the unit 30, 35 and the lugs 450 permitting slight angular displacement of the unit relative to the yoke 31.

After the drill point has been thus properly positioned with reference to a marking point, the operator may lower the unit 30 until it rests upon 40 the legs 37, 38 with the drill 40 rotating in the punch mark. By pressing the button 99 in the center of the hand wheel 97, the automatic operation of the machine immediately proceeds. The pressing of the button 99 actuates the auxiliary 45 clamp control valve 154 and thereby causes shifting of the main clamp control valve 152 so as to close the clamp and draw the unit 30 into firm engagement with the beam 34, with a pressure which greatly exceeds the drill pressure, thus 50 locking the unit 30 to the beam. By providing this excessive clamping pressure, the torque reaction induced by the drill 40 is overcome and the laminations of the structure are clamped tightly together so as to prevent chips from becoming lodged between the laminations.

The last portion of the movement of the clamp actuating slide 126 causes the clutch control valve 153 to be actuated, to thereby engage the feed clutch and move the drill 40 downwardly. 60 The downward feed of the drill 40 continues until the drill point has penetrated the adjacent laminations of the beam 34, whereupon the upper element 157 on the rod 156 will be engaged by the pin 159 on the balance piston rod 93, the latter being moved upwardly as the drill 40 moves 65 downwardly and vice versa. When the control rod 156 is thus moved by the pin 159 it first actuates the valve 151 of the balance cylinder and thereby produces an unbalanced condition in the cylinder 91 through the valve controlled pipe 180, tending to withdraw the drill from the hole. Actual withdrawal is however resisted due to the fact that the feed clutch is still engaged, and the rod 156 will continue its movement until the 70 clutch control valve 153 is engaged and moved to

release the feed. The drill 40 is thereafter rapidly withdrawn from the hole, but the position of the drill unit 30 remains unchanged.

After the drill 40 has been withdrawn from a completed hole, the pin 159 on the plunger rod 93 comes into engagement with the lower element 153, thus actuating the control rod 156 to release the clamping mechanism, and immediately thereafter causes the pressure within the balancing cylinder 91 and on the opposite sides 10 of the piston 92 to be equalized, thus stopping the withdrawal movement of the drill 40 and placing the machine in condition for subsequent operation. It will be apparent that all of these several operations are performed automatically and in 15 sequence upon manipulation of the button 99.

If the operator has made a mistake in the location of the hole after the machine has been placed in operation, he can stop further advance of the drill by manipulating the handle 160 on 20 the control rod 156, to cause the elements 157, 158 to function exactly as if the release had been effected automatically. If the drill 40 is not cutting properly, the operator can release the feed at any time with the aid of the hand lever 25 294, and since the spindle 66 is balanced, the hand wheel 97 may be freely turned to move the drill out of the hole which is being formed, for inspection or otherwise, without disturbing the clamping mechanism or the position of the unit 30. It is also possible, if the drill has been moved into position with the aid of the hand wheel 97, to resume the automatic drilling operation at any time with the aid of the feed control handle 204.

If the laminations of the beam 34 are not perfectly flat, they are apt to buckle after the clamp has been released. It is therefore frequently desirable to clean away the chips before releasing the clamp, so as to prevent chips from becoming lodged between the laminations. By turning the handle 168 of the balancing valve 151, to condition the machine for horizontal drilling, all operations will follow the same sequence just described, and will be performed automatically, 45 with the exception that the clamp need not be released at the end of the cycle, and instead may be released by the operator after cleaning or removal of the chips has been effected. When the drill is to be repointed by grinding, the spindle 50 66 may be moved downwardly with respect to the unit 30 to make the spindle socket accessible for driving the drill 40 therefrom, without actuating the trip elements 157, 158, by turning the control rod 156 about its longitudinal axis to the position 55 of the handle 160 indicated in dot and dash in Fig. 16.

It will thus be apparent that the handles 160, 163, 185 and 204 and the hand wheel 97, provide simple and highly effective means for manually controlling the various operations of the machine which are automatically effected under ordinary conditions by merely pressing the button 99. The speed of rotation of the drill 40 may be readily varied by substituting other gears for the speed reduction gears 82, 83 shown in Fig. 8, and the gears 128, 121 may also be replaced by other gears in order to vary the amount of feed of the drill 40 for each revolution of the spindle 66. The operation of the machine is also susceptible of accurate control by means of the valve 182, needle valve 201, and the control valves in the exhaust lines 200, and the latches coacting with the control valves 151, 152, 153 serve to definitely position these valves, for the various 70 75

operating conditions. The latch 165 cooperating with the flanged element 161 of the control rod 156, likewise serves to definitely position this rod, and the levers 209, 211, which are actuated by one of the slides 126 of the clamping mechanism, function during ordinary operation to shift the valve 153 through the latch 206 carried by the lever 209.

From the foregoing description it will be apparent that the improved perforating machine is highly flexible in operation and functions automatically to clamp, drill and release in accordance with the various settings of the control valves represented diagrammatically in Figs. 21 to 26 inclusive. The fluid pressure actuated servo-motors effectively perform their several functions and their normal automatic actuation is at all times under hand control. The suspension mechanism for the perforating unit 30 permits universal adjustment thereof to cooperate with any portion of a beam 34, and the unit can be shifted throughout a considerable area. By providing interchangeable clamping means adapted for cooperation with any portion of a beam 34, the beam 34 may be definitely located and retained in position during the entire drilling thereof, thus eliminating necessity of subsequent reaming of the holes in order to insure alignment thereof through a number of laminations. The perforating unit may be operated to rapidly drill a succession of holes disposed at any angle and will greatly reduce the cost of assembling laminated beam structures of various types. The releasable clamping mechanism shown in Fig. 2 permits convenient removal of the unit 30 from a beam structure of the type illustrated, and the various types of clamps may be readily applied to the unit to permit use thereof in conjunction with various portions of a complex beam structure.

It should be understood that it is not desired to limit the invention to the exact details of construction and to the precise mode of operation herein shown and described, for various modifications within the scope of the claims may occur to persons skilled in the art.

It is claimed and desired to secure by Letters Patent:

1. In combination, a portable drill press, means carried by said press for supporting the weight thereof independently of the tool directly upon a piece of work to be drilled, a clamp arm carried by said drill press and cooperable with the work piece in opposition to said supporting means to clamp the work near the point of drilling, and means controllable by the clamping action to automatically actuate the drill spindle.

2. In combination, a drill press having means for supporting the weight thereof independently of the tool directly upon a piece of work to be drilled, a clamp arm carried by said drill press and cooperable with the work piece in opposition to said supporting means to clamp the work piece near the point of drilling, and means controllable by the movement of said clamp arm toward said supporting means to automatically advance the drill spindle.

3. In combination, a drill press having means for supporting the weight thereof independently of the tool directly upon a piece of work to be drilled, a clamp arm carried by said drill press and cooperable with the work piece in opposition to said supporting means to clamp the work piece near the point of drilling, and means controllable by the movement of the drill spindle away from

the work for automatically moving said clamp arm away from said supporting means.

4. In combination, a drill press having means for supporting the weight thereof independently of the tool directly upon a piece of work to be drilled, a clamp arm carried by said drill press and cooperable with the work piece in opposition to said supporting means to clamp the work piece near the point of drilling, means controllable by the movement of said clamp arm toward said supporting means to automatically advance the drill spindle, and means controllable by the movement of the drill spindle away from the work for automatically moving said clamp arm away from said supporting means.

5. In combination, a portable drill press, means for rotating the drill spindle, work clamping means carried directly by said drill press, a fluid pressure actuated servo-motor for actuating said clamping means, another fluid pressure actuated servo-motor operable by the movement of said clamping means for controlling the feeding movement of the drill spindle, and still another fluid pressure actuated servo-motor for releasing said feed controlling servo-motor and for counter-balancing the weight of the drill spindle.

6. In combination, a portable drill press, a motor for rotating the drill spindle, work clamping means carried directly by said drill press, a fluid pressure actuated servo-motor for actuating said clamping means, another fluid pressure actuated servo-motor operable by the movement of said clamping means for controlling the feeding movement of the drill spindle, and still another fluid pressure actuated servo-motor for releasing said feed controlling servo-motor and for subsequently withdrawing and finally counter-balancing the weight of the drill spindle, said servo-motors being adapted to function while said motor continues to rotate the drill spindle.

7. In combination, a portable drill press, means for movably suspending said drill press, means carried by said drill press and operable independently of the drill to clamp the opposite sides of a piece of work adjacent to the zone of action of the drill, means for supporting the drill press from said suspending means to permit movement of the drill in various angular directions, and means controllable by said clamping means for effecting automatic advancement of the drill irrespective of the selected angle at which drilling is being effected.

8. In combination, a portable drill press comprising a drill spindle and a motor for driving said spindle, suspension means coacting with said drill press near the center of gravity thereof, self-locking means for effecting angular adjustment of said drill press relative to said suspension means, work clamping means carried by said drill press and operable independently of the drill to support the press, and means controllable by said clamping means for effecting axial movement of said spindle.

9. In combination, a portable drill press comprising a drill spindle and means for driving the same, means for effecting angular displacement of said drill press bodily about an axis and for automatically locking the same in angularly adjusted position, and independent means for effecting vertical and horizontal bodily displacement of the drill press.

10. In combination, a portable drill press having an axially movable spindle, means for rotating said spindle, a fluid pressure actuated clutch actuating servo-motor for controlling the movement

of said spindle along its axis, means for arresting said movement and for reversing the direction of advancement of said spindle at a predetermined moment, and common means for controlling said servo-motor and said reversing means.

5 11. In combination, a portable drill press having an axially movable rotary spindle, means for rotating said spindle, a fluid pressure actuated clutch actuating servo-motor for controlling the axial advancement of said spindle, a fluid pressure actuated servo-motor functioning independently of said clutch actuating servo-motor to arrest and reverse the direction of advancement of said spindle, and independent manually operable means for axially advancing said spindle in either direction.

10 12. In combination, a portable drill press having an axially movable drill spindle, a fluid pressure actuated clutch actuating servo-motor having a plunger for controlling the axial advancement of said spindle, means for establishing balanced fluid pressures upon said spindle, and manually operable means for moving said spindle and said plunger when the pressures have been thus balanced.

15 13. In combination, a drill press having means for supporting the same independently of the tool directly against a piece of work to be drilled, a clamp arm carried solely by said drill press and cooperable with the work piece in direct opposition to said supporting means to clamp the work piece near the point of drilling, and means controllable by the movement of the drill spindle relative to the work for automatically moving said clamp arm.

20 14. In combination, a portable drill press hav-

ing a rotary drill spindle, work clamping means carried directly by the drill press and cooperable with the work adjacent to the axis of movement of said spindle, a servo-motor for automatically actuating said clamping means in response to movement of said spindle, a clutch actuating servo-motor operable to control the feeding movement of said spindle, and another servo-motor for releasing said clutch actuating servo-motor and for withdrawing said spindle from the work.

25 15. In combination, a portable drill press having a rotary drill spindle, work clamping means carried directly by the drill press and cooperable with the work adjacent to the axis of movement of said spindle, a servo-motor for automatically actuating said clamping means in response to movement of said spindle, a clutch actuating servo-motor operable to control the feeding movement of said spindle, and another servo-motor for releasing said clutch operating servo-motor and for successively withdrawing said spindle from the work and counterbalancing the weight thereof.

30 16. In combination, a portable drill press having an axially movable drill spindle, a fluid pressure actuated clutch actuating servo-motor having a plunger for controlling the axial advancement of said spindle, a fluid pressure actuated servo-motor for releasing said clutch actuating servo-motor and for subsequently withdrawing and finally counterbalancing the weight of said spindle, and common control means for effecting actuation of said servo-motors.
